UNITED STATES PATENT OFFICE

LEWIS F. WILLIAMSON, OF HARRISONVILLE, MISSOURI

OIL BURNER

Application filed November 25, 1927. Serial No. 235,651.

This invention relates to an oil burner designed for use in stoves and furnaces, one of the objects being to provide a simple and efficient device which will not become clogged with carbon and can burn a low grade of fuel.

A further object is to provide a burner which does not require the use of a blower or other mechanism likely to get out of order but which, nevertheless affords ample means for effecting a thorough mixing of air and fuel while the burner is in operation.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a top plan view of the burner.

Figure 2 is a side elevation thereof.

Figure 3 is a section on line 3—3, Figure 1, the supply pipe being shown in elevation.

Figure 4 is an enlarged section on line 4—4, Figure 1.

Referring to the figures by characters of reference 1 designates the base of the burner which can be of any desired contour provided with a central orifice 2 through which air is adapted to flow freely. Formed in the top face of the base 1 concentric with the opening 2 is a gutter 3 into which opens a fuel supply pipe 4 extending from any suitable source.

Overlying the base 1 is a dome-like spreading plate 5 the marginal portion of which is supported above the center of the gutter 3, there being radial wings 6 extending from this plate and bearing on the base 1 so as to support the marginal portion of the plate away from the walls of the gutter 3. The wings 6 can be detachably held in position by any suitable means, such as bolts 7 extending through the base. The gutter is pro-

vided with a wick 8 formed of loosely arranged asbestos fibers which partly fill the gutter but offer little if any resistance to the free flow of air under the marginal portion of the plate 5.

In practice it is designed to use a base 1 which will rest on the grate bars of the stove or furnace and practically close communication between the fire box and the ash pit except through the orifice 2. The fuel to be used is supplied to the gutter 3 from the pipe 4 and will spread along the gutter and be absorbed by the wick 8. When this fuel is lighted combustion will be supported by the draft of air upwardly through the orifice 2 and radially under the marginal portion of the spreading plate, 5, the mixture of the air with the fuel insuring almost complete combustion. After the burner has been in use for a short time the metal portions thereof become heated to a high temperature and, consequently, the fuel will be vaporized in the wick and thus mix readily with the hot air deflected by the plate 5 and issuing under the margin of the plate.

For the purpose of strengthening the burner it is preferred to provide the same with a rib 9 concentric with the outer edge of the gutter 3 and the wings 6 are formed with shoulders 10 on their lower faces for engaging the outer edges of these ribs, thereby to hold the plate 5 against sliding movement on the base 1. This construction has been illustrated clearly in Figure 4.

What is claimed is:

In combination, a base having an unobstructed air opening extending therethrough, there being a continuous gutter in the top of the base surrounding said opening, a fuel supply pipe opening upwardly through the base into the bottom of the gutter, a dome-like spreading plate above the base and extending over the opening, the marginal portion of said plate being supported above the center of the gutter, the inner portion of the gutter opening into the space beneath this plate and the outer portion of the gutter opening beyond the margin of the plate, a wick consisting of loosely arranged asbestos fibres partly filling the gutter and extending

to the marginal portion of the spreading plate, said wick permitting substantially free passage of air across the gutter, wings radiating from the spreading plate and bearing on the base at points outside of the gutter, and means extending through the wings and base for binding them together firmly.

In testimony that I claim the foregoing as my own, I have hereto affixed my signature.

LEWIS F. WILLIAMSON.
